Primary Examiner — Susan Moon Lee(74) *Attorney, Agent, or Firm* — Dunlap Bennett & Ludwig PLLC; Brendan E. Squire(57) **CLAIM**

The ornamental design for a livestock vaccination cooler, as shown and described.

DESCRIPTION

FIG. 1 is a top front perspective view of the livestock vaccination cooler showing my new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a right elevation view thereof;

FIG. 7 is a left elevation view thereof; and,

FIG. 8 is a top front perspective view thereof, shown with both lids open.

The broken lines shown in the drawings illustrate portions of the livestock vaccination cooler that form no part of the claimed design.

1 Claim, 5 Drawing Sheets(56)
